UNITED STATES PATENT OFFICE.

CHARLES M. ADAMS, OF BUCKHEAD, GEORGIA, ASSIGNOR, BY DIRECT AND MESNE ASSIGNMENTS, OF ONE-HALF TO JACOB H. HIRSCH, OF ATLANTA, GEORGIA, AND ONE-HALF TO MOZES VAN GELDER, OF CHICAGO, ILLINOIS.

MATTRESS-MAKING MACHINE.

1,242,303.

Specification of Letters Patent.

Patented Oct. 9, 1917.

Application filed June 12, 1916. Serial No. 103,172.

To all whom it may concern:

Be it known that I, CHARLES M. ADAMS, a citizen of the United States of America, and a resident of Buckhead, county of Fulton, and State of Georgia, have invented certain new and useful Improvements in Mattress-Making Machines, of which the following is a specification.

The main objects of this invention are to 10 provide an improved mattress making machine having manually operated means for compressing the mattress material and for holding it in its compressed state preparatory to slipping a casing thereover; to provide improved means for readily raising and holding the compressed mattress material in convenient position to slip a casing or mattress cover thereover; and to provide 15 an improved mattress making machine 20 which is inexpensive in construction and simple in operation.

An illustrative embodiment of this invention is shown in the accompanying drawings, in which—

25 Figure 1 is a perspective view of the machine with the upper clamping bars shown spaced above the table of the machine.

Fig. 2 is a side elevation showing how the compressed material is held when slipping the casing thereover.

Fig. 3 is a detail of the cam used in drawing the clamping bars together to compress the mattress material.

In the construction shown a table or support 35 1 is provided upon which mattress material may be placed during the forming and building up of the mattress. This support may be of suitable height and is held spaced above the floor by means of suitable 40 legs 2.

Slats or binding members 3 are placed upon the supporting table 1 previous to placing the mattress filling material 4 thereon, and upper binding members 5 are placed 45 upon the mattress material when the required quantity to make a mattress has been provided.

Compressing means for pressing the material into a compact form between the slats 50 comprise upper clamping bars 6 and lower clamping bars 7. The bars 6 have pairs of links 8 pivotally connected thereto at the ends and which support cams 9 for engag-

ing the lower clamping bars 7. The lower clamping bars 7 normally rest flush with the 55 table in slots 10.

In order that casings 11 may be easily drawn over the mattress material when compressed, the clamping means are constructed to be raised with the binding members and material from the surface of the supporting table. To this end the clamping bars 7 are supported on foot treadles 12 pivoted to the table 1 and having pivotal connection with depending arms 13 secured 60 to the lower clamping bars 7. The foot treadles may be locked in their depressed position by means of gravity actuated pawls or bars 14 pivoted to table 1 and having shoulders 15 adapted to engage a notch in 70 the respective treadles.

In the operation of the device, a plurality of slats 3 are placed upon the supporting table and mattress filling material is placed thereon until the desired weight of mattress 75 is obtained. Other similar slats 5 are then placed upon the mattress and the upper clamping bars 6 are placed transversely upon the slats and the ends of the lower bars 7 are slipped between the links 8 with 80 the cams 9 in the position shown in Fig. 3.

The cams 9 are then moved to their clamping position shown in Fig. 2, thereby drawing the bars toward each other and tightly compressing the mattress material. 85 One of the foot treadles 12 is then depressed sufficiently to be locked by the shoulder 5 of the bar 14 engaging a notch in the corresponding treadle. A mattress casing 11 may then be readily slipped over 90 the end of the compressed material as far as the first clamping bars. These bars are then released and the casing drawn over the material as far as the second set of clamping bars, which may then be released and 95 the casing drawn completely over the compressed material, after which the slats 3 and 5 may be removed. When not in use, the upper clamping bars are stood to one side up against the wall.

100 It will be seen from the foregoing that this machine provides a speedy and efficient method of making mattresses.

Although but one specific embodiment of this invention is herein shown and described, it will be understood that the con-

struction may be altered and details omitted without departing from the spirit of the invention as defined by the following claims.

I claim:

- 5 1. A mattress making machine, comprising a support, upper and lower sets of comparatively rigid laterally disposed binding members for receiving mattress material between said sets, two or more sets of clamping bars adapted to be transversely arranged at intervals along said binding members so as to embrace the same, and means for drawing said clamping bars toward each other for causing said binding members to compress the mattress material whereby a covering may be placed thereover.
- 10 2. A mattress making machine, comprising a support, a plurality of comparatively rigid laterally disposed binding members for receiving mattress material therebetween, two or more sets of clamping bars adapted to be transversely arranged at intervals along said binding members so as to embrace the same, and means comprising links and
- 15 cams carried by one clamping bar of each of said sets, and engaging the other bar of each of said sets for drawing said bars toward each other for causing said binding members to compress the mattress material whereby a covering may be placed thereover.
- 20 3. A mattress-making machine, comprising a support, binding members for receiving mattress material therebetween, clamping bars for embracing said binding mem-

bers, means for drawing said clamping bars 35 toward each other for compressing the mattress material, and means for raising the binding members and clamping bars for permitting a casing to be slipped over the mattress material while in its compressed state. 40

4. A mattress-making machine, comprising a support, binding members for receiving mattress material therebetween, clamping bars for embracing said binding members, means for drawing said clamping bars 45 toward each other for compressing the mattress material, and means for raising the binding members and clamping bars and comprising a foot treadle having operative engagement with said members and bars. 50

5. A mattress-making machine, comprising a support, binding members for receiving mattress material therebetween, clamping bars for embracing said binding members, means for drawing said clamping bars 55 toward each other for compressing the mattress material, means for raising the binding members and clamping bars and comprising a foot treadle having operative engagement with said members and bars, and means for 60 locking said members and bars in their raised position.

Signed at Atlanta this 30th day of May, 1916.

C. M. ADAMS.
